UNITED STATES PATENT OFFICE.

PHILO B. SHELDON, OF ERIE, PENNSYLVANIA, ASSIGNOR TO THE PHILO BURT MANUFACTURING COMPANY, OF JAMESTOWN, NEW YORK.

DESIGN FOR A BODY-BRACE.

SPECIFICATION forming part of Design No. 35,225, dated October 22, 1901.

Application filed August 28, 1901. Serial No. 73,625. Term of patent 14 years.

To all whom it may concern:

Be it known that I, PHILO B. SHELDON, a citizen of the United States, and a resident of Erie, in the county of Erie and State of Pennsylvania, have invented and produced a new and original Design for a Body-Brace, of which the following is a specification, reference being had to the accompanying drawing, forming a part thereof, which represents a front elevation of a surgical appliance embodying my design.

The design presents the appearance of vertically-extending strips *a* and *b*, of which the former are long and the latter short. Between these strips appear lacings *g*, extending throughout the length thereof. To the upper portions of the strips *a* shoulder-straps

c are fastened, and from the outermost strips *b* a waistband *d* extends. Below the waistband *d* appears a stomach-pad *e*, joined to certain of the strips *b* by straps *f*.

Having described my invention, what I claim as new, and desire to secure by Letters Patent, is—

The design for a body-brace, as herein shown and described.

In testimony whereof I have signed my name to this specification in the presence of two subscribing witnesses.

PHILO B. SHELDON.

Witnesses:

J. M. SHERWIN,
L. H. COUSE.
